UNITED STATES PATENT OFFICE

CARL E. TANNEWITZ, OF GRAND RAPIDS, MICHIGAN

DRAWER LOCK MECHANISM

Application filed October 22, 1928. Serial No. 313,977.

The main objects of this invention are:

First, to provide an improved locking means for desk drawers or for a series of drawers which is actuated to locking position from an actuating drawer, the locking means being returned to its open position by gravity when the actuating drawer is unlocked or released.

Second, to provide an improved drawer locking means of the class described which is very simple in its structure and has the parts arranged so that it may be quickly mounted in a desk structure.

Objects pertaining to details and economies of my invention will appear from the description to follow. The invention is defined in the claims.

A structure which is a preferred embodiment of my invention is clearly illustrated in the accompanying drawings in which:

Fig. 1 is a fragmentary view mainly in vertical section on a line corresponding to line 1—1 of Fig. 3, parts being broken away to better show structural details.

Fig. 2 is a fragmentary vertical section on line 2—2 of Fig. 3.

Fig. 3 is a horizontal section on line 3—3 of Figs. 1 and 2.

Fig. 4 is a perspective view of the locking mechanism removed from the desk.

Referring to the drawings, the structure illustrated is an office desk of the type in which I have embodied my improvements and, in general, comprises a suitable cabinet designated by the numeral 1 and provided with a series of drawers 2, 3 and 4 arranged vertically. The central drawer of the desk is shown at 5, this arrangement being common office desk arrangement.

The drawer 5 is provided with a lock or other means for retaining it in closed position shown conventionally at 6. At the rear of the series of drawers I mount a locking bar 7 for vertical reciprocating movement, a pair of brackets 8 being secured to the desk frame and provided with projecting studs 9 engaging the longitudinal slots 10 in the locking bar.

The locking bar has forwardly projecting hooks 11 faced upwardly to engage with the

bottoms of the rear walls of the series of drawers as is illustrated in Fig. 1. The weight of the locking bar and its attached parts is such as to return the locking bar to unlocking position when its actuating means is released.

An actuating lever 12 is pivoted at 13 at the rear of the drawer 5 with its downwardly projecting arm 14 in position to be engaged by the drawer 5 when it is completely closed. The arm 15 of the actuating lever engages an arm 16 projecting laterally from the locking bar so that the locking bar is lifted to locking position when the drawer 5 is fully closed or in the position indicated by dotted lines in Fig. 2. This lifts the drawer engaging members 11 of the locking bar into engagement with the drawers to be locked as shown in Fig. 1.

The arm 15 of the actuating lever is a spring of sufficient stiffness to support the locking bar in locking position, at the same time yielding to permit the closing of one or more of the locked drawers after the locking bar has been lifted.

The weight of the locking parts is such that when the lock 6 is released the drawer 5 is automatically partially opened or moved to the position shown by full lines in Fig. 2, thereby releasing the locked drawers.

My improved locking mechanism is very simple and economical in its parts and at the same time they are strong and durable, no springs being required to move the parts to unlocking position. The spring arm of the actuating lever yields, however, to permit closing of the drawers after the locking bar has been actuated as described.

I have illustrated and described my improvements in an adaptation which is suitable for types of desks which are very extensively used. Other adaptations for particular designs of desks will, it is believed, be obvious to those skilled in the art to which my invention relates.

Having thus described my invention, what I claim as new and desire to secure by Letters Patent, is:

1. In a structure of the class described, the combination of a plurality of drawers hav-

ing downwardly projecting rear walls arranged in a vertical series, a lock actuating drawer disposed at one side of said series of drawers, said lock actuating drawer being provided with a lock, a locking bar mounted for vertical reciprocating movement at the rear of said series of drawers and provided with a plurality of upwardly facing hooks engaging the bottoms of said downwardly projecting rear walls of said series of drawers from below when said locking bar is lifted to locking position, an arm on said bar projecting laterally therefrom to the rear of said actuating drawer, and an actuating lever pivotally mounted at the rear of said actuating drawer to be engaged thereby when in its closed position and provided with a flat spring arm engaging said arm on said locking bar, said spring arm yielding when in actuated position to permit the closing of said series of drawers, the weight of said locking bar and its attached parts being such as to partially open said actuating drawer and return said locking bar to its initial position when the actuating drawer is unlocked.

2. In a structure of the class described, the combination of a plurality of drawers to be locked having downwardly projecting rear walls, an actuating drawer, a locking bar mounted for vertical reciprocating movement and provided with a plurality of drawer engaging members engaging the bottoms of said downwardly projecting rear walls of said drawers to be locked from below when said locking bar is raised to locking position, an arm on said locking bar projecting laterally to the rear of said actuating drawer, and a pivotally mounted actuating lever positioned at the rear of said actuating drawer to be engaged by said actuating drawer when in its closed position and provided with a flat spring arm engaging said arm on said locking bar, said spring arm yielding when the locking bar is in actuated position to permit the closing of said drawers to be locked, the weight of said locking bar and its attached parts being such as to return said locking bar to its initial position and partially open said actuating drawer when the actuating drawer is released.

In witness whereof I have hereunto set my hand.

CARL E. TANNEWITZ.
